UNITED STATES PATENT OFFICE.

SIMON HEITER, OF NEW YORK, N. Y.

DESIGN FOR A PARASOL.

SPECIFICATION forming part of Design No. 19,653, dated February 18, 1890.

Application filed January 22, 1890. Serial No. 337,755. Term of patent 3½ years.

To all whom it may concern:

Be it known that I, SIMON HEITER, a citizen of the United States, residing at New York, in the county and State of New York, have invented a new and original Design for Parasols, of which the following is a specification.

My invention hereinafter described is a design for ladies' parasols. It is applied to the top or cover of parasols, and it consists of interrupted radial bands or stripes on the cover of the parasol.

In the accompanying drawings, Figure 1 shows a side elevation of a lady's parasol, in general form the same as those ordinarily used. Fig. 2 represents a top view of the same.

In the drawings the parts of the broken bands or stripes are represented at *a*, the

spaces between at *b*. The bands or stripes are radial, and the effect is produced by the contrast of the bands or stripes with the ordinary surface of the parasol-cover. The spaces between the bands or stripes are the same as the general surrounding surface of the cover.

I claim as my invention—

The design for a parasol-top, the same consisting of the top or cover of a parasol having interrupted radial bands or stripes, as shown and described.

In testimony whereof I have signed my name to this specification in the presence of two subscribing witnesses.

SIMON HEITER.

Witnesses:

I. DITTEHENIMER,
JAS. FRASER.
